UNITED STATES PATENT OFFICE.

EDWARD MELTZER, OF EGG HARBOR CITY, NEW JERSEY, ASSIGNOR TO LIBERTY CUT GLASS WORKS, OF EGG HARBOR CITY, NEW JERSEY, A CORPORATION OF NEW JERSEY.

DESIGN FOR A GLASS JUG OR SIMILAR ARTICLE.

Application filed May 21, 1926. Serial No. 17,799. Term of patent 7 years.

To all whom it may concern:

Be it known that I, EDWARD MELTZER, a citizen of the United States, residing in Egg Harbor City, in the county of Atlantic and State of New Jersey, have invented a certain new, original, and ornamental Design for Glass Jugs or Similar Articles, of which the following is a specification, reference being had to the accompanying drawings, forming a part thereof, and of which—

Figure 1 is a side elevation, and Fig. 2 is a horizontal section on an enlarged scale on the line 2—2 of Fig. 1, of a glass jug showing my new design.

I claim:

The ornamental design for a glass jug or similar article as shown.

EDWARD MELTZER.
